UNITED STATES PATENT OFFICE.

WILLIAM H. MORGAN, OF ALLIANCE, OHIO, ASSIGNOR TO THE MORGAN ENGINEERING COMPANY, OF ALLIANCE, OHIO.

LADLE-CRANE.

980,321.

Specification of Letters Patent.

Patented Jan. 3, 1911.

Application filed May 7, 1910. Serial No. 560,053.

To all whom it may concern:

Be it known that I, WILLIAM H. MORGAN, of Alliance, in the county of Stark and State of Ohio, have invented certain new and useful Improvements in Ladle-Cranes; and I do hereby declare the following to be a full, clear, and exact description of the invention, such as will enable others skilled in the art to which it appertains to make and use the same.

My invention relates to improvements in ladle cranes,—the object being to provide a crane of compact form and great strength and in which the auxiliary trolley shall be capable of performing all of the work for which such trolleys are ordinarily adapted and in addition, shall be capable of removing and replacing any of the mechanism of the main trolley, also the bridge motor and the mechanism contained in the operator's cage and also of facilitating the installation of the main trolley and of lifting and moving machinery or material situated outside of the main girders.

With these objects in view my invention consists in certain features of construction and combinations of parts as will be herein-after described and pointed out in the claims.

In the accompanying drawings, Figure 1 is a view in vertical cross-section of one embodiment of my improvement, and Fig. 2 is a modification.

1, 1, represent the girders which serve to support both the main trolley 2 and the auxiliary trolley 3. The girders 1, 1, are wide box girders having rails 4, 4, which support the main trolley located vertically over its inner webs 5, 5, and the rails 6, 6, which support the auxiliary trolley located vertically over its webs 7, 7, and hence the entire weight of the main trolley and its load and that of the auxiliary and its load is supported in vertical alinement with the two vertical webs of the girders. The main hoisting chains or ropes 8, 8, depend inside of the girders and are connected in any desired manner to the ladle bar 9. By this arrangement the main trolley may be made of compact form and be adapted to support the weight of the ladle and its contents as

nearly in alinement as is desired with the ladle hooks 10, 10. Should either one of the main hoisting chains or ropes break, the main trolley cannot be overturned as its load is suspended from the main trolley at points 55 inside of the girders 1, 1. The auxiliary trolley 3 is, in effect, a locomotive jib crane being provided with a rotary turntable 11 which is mounted on supporting wheels to insure of its ready operation and is rotated 60 by an electric motor 12 through the medium of suitable gearing not shown, the motor being controlled by electrical connection from the operator's cage. On the turntable 11 is mounted a hoisting drum 13 which carries 65 the main hoisting rope or chain 14 which passes over a sheave 15 mounted near the outer end of the jib 16 which is of sufficient length to project outside of the footwalks 17 attached to the outer sides of the girders 70 1, 1. Upon the turntable is mounted an auxiliary hoisting drum 13^a which is operated by an electric motor 13^b. This auxiliary hoisting drum carries an auxiliary hoisting rope or chain 14^a which passes over a sheave 75 15^a mounted in the outer end of jib 16, and depends therefrom as illustrated in the drawings.

In the operation of a ladle crane the auxiliary trolley is sometimes employed to carry 80 a ladle of molten metal to and discharge it into the large ladle carried by the main trolley, and to facilitate this operation I provide the auxiliary trolley with main and auxiliary hoisting chains or ropes in order to 85 permit the main rope to be used to lift and transport a ladle of molten metal and to tip the ladle by means of the auxiliary rope and thereby discharge its contents into the main ladle. The girders 1, 1, and which constitute the traveling bridge of the crane, are propelled forwardly and backwardly on the trackways of the crane by means of the electric motor 18 secured to the outer side of one of the girders and at any point throughout its length. The auxiliary trolley is provided with a foot-walk 19 having side railing 20 which may extend completely around said trolley and from this footwalk steps or a ladder 21 depend to a point near one of the 95 100

footwalks 17 whereby ready access is had to the auxiliary trolley for inspection or repairs. On the rotary bed of the auxiliary trolley, at a point opposite its jib, is mounted 5 a standard 22 which constitutes a counter-weight and also a support for the inner ends of the braces 23 which are connected at their outer ends to the jib. The auxiliary trolley is provided with safety hooks 24 which 10 extend downwardly and beneath the projecting flanges 25 of the girders and prevent the overturning of the auxiliary trolley while in use.

In the operation of the crane the main and 15 auxiliary trolleys are entirely independent in their operation and movements and the auxiliary trolley may have its rotary table swung around into position for tipping the ladle or doing any other work between the 20 girders which is performed by such trolleys in cranes of ordinary construction, while it is adapted to perform a great variety of additional work. For instance the jib auxiliary trolley may be rotated so as to carry the 25 hoisting rope or chain outside the main girders and enable the auxiliary trolley to be used to lift "skulls" or "spills" or other material or machinery located outside the main girders; also to lift and remove and 30 replace for inspection or repairs the bridge motor or any of the controlling mechanism within the operator's cage, and further owing to the fact that the auxiliary trolley is located above the main trolley, it may be 35 utilized for removing and replacing any part of the main trolley. In installing the crane, the auxiliary having been installed, can be utilized in lifting and installing the main trolley, bridge motor and other parts 40 of the crane.

In the modification represented in Fig. 2, the auxiliary trolley is provided with two projecting arms 16, 16 to provide for the use of two separate and independent auxiliary hoisting ropes or chains. In this construction instead of supporting the main and auxiliary trolleys on two girders, four 45 separate and independent girders are employed, the main trolley being supported by the main girders 26 and the auxiliary trolley by the auxiliary girders 27. The auxiliary trolley in this construction is provided 50 with safety hooks 28 which depend between the main and auxiliary girders and project 55 outwardly beneath the auxiliary girders so as to effectually prevent the overturning of the auxiliary trolley.

In the operation of ladle cranes the auxiliary trolley is called into action only 60 occasionally and when it is not in actual use it requires to be at all times under the watchful care of the crane operator to see to it that the auxiliary hoisting rope or chain

does not interfere with the ladle bar, while in the operation of my improved crane, the auxiliary hoist rope or chain may be swung outside of the girders and entirely out of the path of the ladle bar and when it is desired to use the auxiliary trolley to tip the ladle or perform any other work between the girders 70 its hoisting rope or chain may be quickly swung into position between the girders, after which it may be swung outside of the girders again where it is always in readiness for use for any of the several purposes 75 which I have heretofore pointed out.

As it is evident that my improvements will admit of a wide departure from the particular construction and arrangement of parts shown and described without departure from the spirit of my invention, I would have it understood that I do not restrict myself to the particular construction shown and described, but,—

Having fully described my invention what 85 I claim as new and desire to secure by Letters-Patent, is,—

1. In a ladle crane, the combination with a main trolley, of an auxiliary trolley provided with a hoisting rope or chain supported on a transverse adjustable arm. 90

2. In a ladle crane, the combination with a main trolley, of an auxiliary trolley located outside the main trolley and provided with a hoisting rope or chain, and means for 95 operating the same either inside or outside the girders supporting the main trolley.

3. In a ladle crane, the combination with a main trolley, of an auxiliary trolley located above the main trolley and provided 100 with a hoisting rope or chain, and means for operating the same at a point outside or inside the main girders.

4. In a ladle crane, the combination with a main trolley, an auxiliary trolley, and girders, each provided with two sets of rails for supporting said trolleys, of a rotary table or support on the auxiliary trolley for carrying the auxiliary hoisting rope or chain. 105

5. In a ladle crane, the combination with the main and auxiliary trolleys, of two girders for supporting the same, and safety hooks attached to the auxiliary trolley and extending downwardly beneath the outwardly projecting flanges on said girders. 115

6. In a ladle crane, the combination with the main trolley, of an auxiliary trolley located above the main trolley, said auxiliary trolley being provided with a footwalk and with a ladder or steps extending downward in close proximity to one of the footwalks on one of the supporting girders. 120

7. In a ladle crane, the combination with the main trolley, of an auxiliary trolley located above the main trolley and provided 125

with an outwardly projecting arm for carrying its hoisting rope or chain, and with a counter weight opposite said arm.

8. In a ladle crane, the combination with the main trolley, of an auxiliary trolley provided with main and auxiliary hoisting chains or ropes.

9. In a ladle crane, the combination with a main trolley, of an auxiliary trolley located above the main trolley and provided

with a rotatable jib carrying main and auxiliary hoisting ropes or chains, substantially as set forth.

In testimony whereof, I have signed this specification in the presence of two subscribing witnesses.

WILLIAM H. MORGAN.
